Original application June 30, 1955, Serial No. 519,136. Divided and this application December 3, 1956, Serial No. 625,695.

2 Claims. (Cl. 112—262)

This invention relates to improvements in seams for uniting two or more layers of work by adhesive fastenings employed in combination with conventionally arranged thread.

The subject matter herein contained has already been disclosed in an application for United States Letters Patent, Serial No. 519,136, filed June 30, 1955, in the names of the present inventors, of which application the present one is a division.

The above-identified parent application discloses a novel machine which may be utilized to insert charges of an adhesive agent into the needle perforations of a thread seam in the work or alternatively to fasten multiple layers of work together solely by adhesive charges regularly spaced from one another to form a seam, the adhesive charges in either case being injected into the work at high velocity.

In order to extend the utility of thread seams for uniting work pieces and to overcome some of their inherent deficiencies, it has become common practice in recent years to employ a fluid adhesive agent to form cement for bonding the thread of conventional seams to the work being operated upon. To be effective, however, cemented seams must provide improved bonding of the thread to the work while avoiding objectionable results characteristic to the presence of the cement. Such objectionable results appear when an adhesive agent is applied to the thread exposed between the needle perforations of the seam, either when the thread is fully coated with an adhesive agent at the time that the stitches are formed or when the adhesive agent is deposited on the exposed thread only. In either case the formation of hardened cement on an exposed surface objectionably stiffens the work in the area of the seam and increases the possibility of marring or otherwise spoiling the appearance of the work by surplus deposits of the adhesive agent. Such surplus deposits of cement, moreover, may interfere with subsequent operations often necessary for finishing the sewn article. In addition, when the thread is fully covered with an adhesive agent, difficulties are experienced in tightening the stitches and further, the adhesive agent may be thrown off against the work-feeding and stitch-forming devices of the sewing machine and interfere with their satisfactory operation.

In order to avoid the difficulties caused by the presence of a liquid adhesive agent on exposed work surfaces, one expedient has been to insert adhesive plugs in semi-solid state within the needle perforations. Such a seam is disclosed in United States Letters Patent, No. 2,486,531, granted November 1, 1949, upon application of Clyde L. Knott. The patented seam structure is particularly useful for attaching outsoles of shoes and for uniting layers of other relatively thick work. When properly inserted such seams provide a firm bond between the loops of thread and the work. Because the location of the plugs in the work and hence the quality of the seam depend on a variety of interacting factors, their satisfactory insertion requires care and close attention of a highly

2

skilled operator. The factors which affect the quality of the patented seam include, as in uncemented seams, relative sizes of needle, awl, and thread, composition of the thread and of the work being operated upon, and, in addition, the character, size, shape, and plasticity of the plugs at the time of their insertion into the work. Any appreciable variation in one factor requires an accurate compensating adjustment in one or more of the others by a skilled operator.

10 It is an object of our invention to provide seam structures combining thread and a fluid adhesive agent which may be successfully inserted in work pieces by an operator having no greater skill than is necessary for forming uncemented seams. Another object is to provide an adhesive bonded lock stitch seam passing through multi-layer work pieces through relatively long perforations of a diameter less than the combined thicknesses of the layers. A further object is to provide a cemented thread seam in which insertion of the thread may be regulated independently of the cementing operation. Still another object is to provide a cemented thread seam in which there is a maximum area of bond between the work and thread without the necessity of having surplus deposits of cement formed on exposed work surfaces. Another object is to provide a seam structure for uniting multiple layer work and a barrier against the entry of moisture between the layers, both in a single operation. Another object is to waterproof the fibers of thread contained in the needle perforations of a conventional thread seam to prevent deterioration of the thread.

30 In the achievement of the foregoing objects a principal feature of our invention resides in a seam structure inserted in one or more layers of work in a conventional manner through perforations intersecting an interface of the layers and formed at least in part of adhesive agent hardened into cement within the perforations with connections between the layers. The adhesive agent is conveniently introduced into the perforations as a series of separate charges for reinforcing a continuous thread seam, one charge being introduced in each perforation and joined with each other between the layers by the apparatus of the above-identified parent application. By means of this apparatus a charge of adhesive agent is injected at high velocity into each needle perforation, completely impregnating the thread therein and anchoring the thread firmly to the work by an enlargement within the perforation at the interface between the layers. The size of the enlargement may be regulated to form a junction with the charges in adjacent perforations thereby providing a continuous seal the entire length of the seam at the interface, if such is desirable in a given work piece, to exclude moisture or other foreign matter. The adhesive agent, preferably thermoplastic, thoroughly coats the fibers of the thread not only improving their strength characteristics but also making them impervious to moisture which would otherwise cause premature deterioration.

60 The foregoing objects, features, and advantages of our invention will be more fully understood from a description of an illustrative embodiment of the invention taken in connection with the accompanying drawings, in which

Fig. 1 is a view in partial cross section, showing a seam structure embodying the present invention and the portion of the apparatus of the parent application by which the seam structure may conveniently be inserted; and

Fig. 2 is a detail view greatly enlarged in cross section of a single needle perforation showing the relative disposition of the thread and the cement therein deposited for a slightly modified seam structure.

Referring more particularly to Fig. 1 of the drawings,

a form of seam embodying the present invention is there-
in illustrated. The work operated upon is composed of
multiple superimposed work layers, shown for the sake
of simplicity as consisting of two parts 4 and 6, com-
prising the sole and welt respectively of a shoe. The
stitches are inserted by the usual devices including an awl
8 and a needle 10 acting to form a series of perforations
passing through the work layers 4 and 6 and to carry
through the perforations and across an outer surface of
the work successively loops of a continuous length of
machine or needle thread 12. A similar continuous
length of locking thread 14 is inserted into and inter-
locked with each projecting loop of needle thread to
form a conventional lock stitch seam, the points of in-
terlocking engagement between the threads being located
approximately half way between the surfaces of the out-
sole 4. After each stitch is formed and tightened to
bring the point of interlocking engagement of the threads
into the outsole, a charge of high velocity, hot melt liquid
adhesive agent is injected into the stitch perforation.

The adhesive injecting apparatus, more fully described
in the above-identified parent application, includes in
addition to an impeller which meters and propels the
adhesive charges, a special presser foot 16 having a
nozzle 18 in communication through an internal passage
20 in the presser foot with the lower end of a flexible tube
22. The upper end of the tube 22 is connected to the
impeller. The presser foot cooperates with a work sup-
port 24 of conventional design for gripping and feeding
the work. The nozzle 18 is positioned in registration
with a needle perforation two stitches beyond the point
of needle operation. The impeller is provided with
separate adjusting means for changing the velocity of
delivery and volume of the charge, more fully disclosed
in the parent application, which charge is injected into
the needle perforation in line with the nozzle 18.

The velocity and quantity of adhesive charge may be
so determined that it continues in motion by its own
inertia through each perforation in the outsole 4 to an
interface 26 between the outsole and welt, the forepart
of the charge being carried slightly beyond the point
where the threads 12 and 14 are interlocked and the in-
terface between the layers. As the velocity of charge
is reduced by the resistance offered in filtering through
the interstices of the thread it loses a substantial quantity
of its heat especially along the area of the advancing
front at the forepart of the charge. The reduction in
velocity and solidifying action suddenly becomes critical
and a dam 28 of cement is formed having a more or less
solid convex area behind which the remainder of the
adhesive charge builds up. Deeper penetration of the
adhesive may be obtained on a given work piece by an
increase in the velocity of injection. The advancing
adhesive charge bringing with it the remainder of the
heat initially contained therein, exerts a pressure on the
solid dam 28 especially along the sides of a perforation,
whereupon a portion of the charge spreads out to a sub-
stantial degree and migrates along the adjacent inter-
face of the layers formed by the outsole and the welt.
The quantity of the charge and the temperature to which
it is raised may be so adjusted that the pressure on the
sides of the perforation causes the charge to migrate
more than half way from the perforation between the
layers toward the adjacent charge, as shown in Fig. 1,
thus forming a conjunction with the previous charge or
the pressure may be insufficient to form a conjunction,
as in Fig. 2.

Although the completed seam constructed in this way
appears similar in all respects to one having no adhesive
reinforcement, it possesses far greater strength and dur-

ability. The velocity with which the adhesive agent is
carried into the perforation is sufficient to prevent any
external accumulation at the surface of the work piece
through which the adhesive enters and the dam 28 forms
a barrier for stopping the penetration of adhesive charge
short of the other surface. Since the work layers are
firmly pressed together at the point of adhesive injection
by the tightened thread stitches the enlargement at the
interface is limited to a thin section between the layers,
the enlargement being of minimum thickness at the edge
most remote from the perforation through which the
adhesive agent is injected. Such a thin section of adhe-
sive agent forming cement under the heavy pressure of
the stitches yields a bond between the layers which is far
stronger than would be obtained without the benefit of
the pressure. Another advantage of the thin section of
cement is that the improved strength characteristic of
the seam is obtained without appreciable loss of flexibility
in the work. Greater durability of the seam is obtained
by distributing a high velocity of adhesive charge through-
out the length of each perforation filling any voids be-
tween the thread and the work and securely bonding the
thread to the sides of the perforation. Such distribu-
tion of the adhesive renders the thread impervious to
moisture and prevents relative movement between the
parts, two causes of premature failure in uncemented
seams.

The nature and scope of the invention having been in-
dicated and a particular embodiment having been de-
scribed, what is claimed is:

1. A thread seam uniting layers of dense and resistive work, such as leather shoe parts having, between outer faces of the work, a series of perforations each of a diameter less than the combined thicknesses of the layers, and a continuous lockstitch having interlocking loops within the perforations and having lengths of thread passing from one perforation to another across the outer surface and in engagement with the work, the loop locks being positioned between the said faces, in combination with a discrete charge of hardened cement in each perforation entirely between the outer surfaces of the work, anchored to the work by a substantial enlargement of the cement at an interface between layers, and bonded to a substantial part of the thread within the perforation.
2. A thread seam uniting layers of dense and resistive layers of work, such as leather shoe parts, having, be-
tween outer faces of the work, a series of perforations each of a diameter less than the combined thicknesses of the layers and a continuous lockstitch having interlocking loops within the perforations and having lengths of thread passing from one perforation to another across the outer surface and in engagement with the work, the loop locks being positioned between the said faces, in combination with a discrete charge of solidified thermoplastic adhesive in each perforation entirely between the outer surfaces of the work, anchored to the work by a substantial enlargement of the cement at an interface between the layers, and bonded to the thread within the perforation.
